UNITED STATES PATENT OFFICE.

LLOYD V. LEWIS, OF EDGEWOOD BOROUGH, PENNSYLVANIA, ASSIGNOR TO THE UNION
SWITCH & SIGNAL COMPANY, OF SWISSVALE, PENNSYLVANIA, A CORPORATION
OF PENNSYLVANIA.

RAILWAY-TRAFFIC-CONTROLLING APPARATUS.

Application filed April 28, 1924. Serial No. 709,398.

To all whom it may concern:

Be it known that I, LLOYD V. LEWIS, a citizen of the United States, residing at Edgewood Borough, in the county of Allegheny 5 and State of Pennsylvania, have invented certain new and useful Improvements in Railway-Traffic-Controlling Apparatus, of which the following is a specification.

My invention relates to railway traffic controlling apparatus, and particularly to apparatus of the type comprising train-carried speed governing mechanism controlled by energy received inductively from the track-way.

15 I will describe one form of apparatus embodying my invention and will then point out the novel features thereof in claims.

In the accompanying drawings, Fig. 1 is 20 a diagrammatic view showing one form of trackway apparatus embodying my invention. Fig. 2 is a view partly diagrammatic and partly in section, showing one form of train-carried apparatus suitable for co-operation with the trackway apparatus shown 25 in Fig. 1 and also embodying my invention.

Similar reference characters refer to similar parts in each of the views.

Referring first to Fig. 1, the reference characters 1 and 1^a designate the track rails 30 of a railway along which traffic normally moves in the direction indicated by the arrow. These rails are divided by insulated joints 2 into a plurality of sections A—B, B—C, C—D, etc.

35 Each section is provided with a track circuit comprising a source of alternating track circuit current connected across the rails at the exit end of the section, and a track relay 40 receiving energy from the rails at the entrance end of the section. The immediate source of track circuit current for each section is a transformer designated by the reference character 6 with a suitable exponent, the secondary of which transformer is connected across the rails of the section. Alternating current is supplied to the primary of each transformer 6 from a transformer 3 through a pole-changer P, and the primary of each transformer 3 is connected across a 45 transmission line 5 which is constantly supplied with alternating current from a generator 4. Each pole-changer P is operated in accordance with traffic conditions in advance, as will be explained hereinafter. The

track relay for each section is designated 55 by the reference character R with a suitable exponent, and in the form here shown each relay comprises two windings 7 and 8. Winding 7 is connected with the rails of the corresponding section while winding 8 60 is constantly supplied with alternating current of fixed relative polarity from the transmission line 5. The electrical connections between windings 8 and the transmission line are omitted from the drawing for the purpose of simplification. Each track relay comprises a contact 9 which is swung to the right or to the left according as the relay is energized by track circuit current of normal relative polarity or reverse relative 70 polarity, that is, according as the pole-changer P for the corresponding track circuit is in normal or reverse position.

In the apparatus shown in Fig. 1, each track section is provided with a trackway signal designated by the reference character S with a suitable exponent, each of which signal is of the three-position semaphore type, arranged to indicate "Proceed", "Caution", and "Stop". It is understood 80 that these signals are controlled by the track relays R in any usual manner, but inasmuch as such control forms no part of my invention, the controlling circuits are omitted from the drawing. In accordance with 85 usual practice each signal will indicate Stop when the associated track section is occupied, Caution when the associated track section is unoccupied and the section next in advance is occupied, and Proceed when the associated section and the section next in advance are both unoccupied.

In the arrangement of apparatus here shown, each pole-changer P is mechanically operated by the associated signal S and in 95 such manner that the pole-changer is in normal position when the signal indicates Proceed and Caution, but in reverse position when the signal indicates Stop.

Means are also provided for supplying 100 to each section a second alternating train governing current which flows through the rails of the section in multiple. For this purpose an impedance 12 is connected across the rails adjacent the entrance end of each section and a second impedance 13 is connected across the rails adjacent the exit end of the section. This second current,

which I will term the "loop" current, is furnished by a transformer designated by the reference character E with a suitable exponent, the secondary winding 11 of which is connected with the middle points of the two impedances 12 and 13 in the associated section by wires 98 and 99. The middle point of the primary 10 of each transformer E is connected with the lower 10 arm of the adjacent pole-changer P, by a wire 97, and the two end terminals of the primary 10 are connected with the two fixed contact members respectively of contact 9 in the adjacent track relay R. The 15 movable member of each contact 9 is connected with the upper arm of the associated pole-changer P by a wire 96. It follows that the relative polarity of the loop current for any given section is determined jointly 20 by the position of the associated pole-changer P and by the position of contact 9 of the track relay for the section next in advance.

As shown in the drawing, the section immediately to the right of point D is occupied by a train W, so that track relay R^D is de-energized and signal S^D indicates Stop. Pole-changer P^D is in the reverse position, so that track circuit current of reverse relative polarity is supplied to the rails of section C—D. Inasmuch as track relay R^D is de-energized, the primary circuit for transformer E^D is open, so that the supply of loop current to the rails of section C—D 30 is discontinued. Track relay R^C is energized in reverse direction, so that signal S^C indicates Caution and pole-changer P^C is in the normal position. Track circuit current of normal relative polarity is, therefore, 35 supplied to the rails of section B—C. Alternating current of normal relative polarity is supplied to the upper half of the primary winding 10 of transformer E^C, whereby loop current of what I will term "reverse" relative polarity is supplied to the rails of section B—C. Track relay R^B is energized in normal direction so that signal S^B indicates Proceed, and so it follows that pole-changer P^B is in the normal position and track circuit current of normal relative polarity is 40 supplied to the rails of section A—B. Alternating current of normal relative polarity is supplied to the lower half of the primary winding 10 of transformer E^B, so that loop current of what I will term "normal" relative polarity is supplied to the rails of section A—B.

Referring now to Fig. 2, the train-carried mechanism comprises a pair of magnetizable cores 14 and 14^a located in front of the forward axle and disposed above the two track rails 1 and 1^a, respectively. These cores are provided with windings 16 and 18^a, which I will term "track" windings of the mechanism. Also mounted on the train

at a convenient point is a pair of magnetizable cores 15 and 15^a also disposed above the rails 1 and 1^a, respectively, and provided with windings 17 and 17^a, which I will term the "loop" windings. 70

The track and loop windings control the supply of energy to the two stator windings 19 and 20, respectively, of an induction motor relay F, and suitable amplifying apparatus 18 is preferably introduced between each pair of windings and the relay. The relay F also comprises a rotor 21 controlling a plurality of contacts 22, 23, 24 and 25. The relay F and the pick-up apparatus for supplying energy thereto, is so arranged that when alternating track circuit and loop currents of normal relative polarity are flowing in the track rails the contacts 22, etc. are swung to the right, when the relative polarity of either of these currents is reversed the contacts are swung to the left, and when either alternating current is discontinued the relay contacts occupy intermediate or vertical positions. 85

The train is provided with a signaling means G controlled by relay F and comprising three electric lamps A', R' and S', arranged when energized to indicate respectively "Authorized speed," "Restricted speed" and "Slow speed". When relay F is energized in normal direction the authorized speed lamp A' is lighted by virtue of a circuit which passes from terminal B' of a suitable source of current through contact 22, lamp A' and contact 23 to terminal O of the same source of current. When relay F is energized in the reverse direction, the restricted speed lamp R' is lighted through a circuit similar to that for lamp A' but including the left-hand points of contacts 22 and 23. When relay F is de-energized, the slow speed lamp S' is lighted through a circuit which passes from terminal B' through contact 24, lamp S, and contact 25 to terminal O. 100 105 110

The train is provided with speed governing apparatus which is controlled by an unlimited speed magnet 26^U and a high speed magnet 26^H. Magnet 26^U is connected in multiple with the authorized speed lamp A', and so it is energized whenever relay F is energized in the normal direction. High speed magnet 26^H is connected in multiple with the restricted speed lamp R', and so it is energized whenever relay F is energized 120 in the reverse direction. Magnet 26^U controls a valve 49 in such manner that this valve occupies its upper position when the magnet is de-energized, and its lower position when the magnet is energized. Magnet 26^H controls a valve 68 in a similar manner. The valves 49 and 68 control a relay valve mechanism 92 comprising an unlimited speed relay slide valve K^U and a high speed relay slide valve K^H. The train is provided 125 130

with a speed governor V comprising a centrifugal device T driven by a wheel of the train and operating a crosshead 93, which in turn coacts with a high speed valve 27^H, 5 a low speed valve 27^L, and a blow-down valve 28. The speed governor V and the relay valve mechanism 92 co-operate to control a brake application valve Y comprising a slide valve 35 and a piston 36 provided 10 with a restricted port 36^a. When the slide valve 35 is in the position shown in the drawing, it operates to prevent an automatic application of the brakes, but when this valve is shifted to the right it cuts off main 15 reservoir pressure from the engineer's valve M and causes an automatic application of the brakes through the medium of ports and pipes which are not shown in the drawing. Air pressure is normally supplied to 20 the chamber above the slide valve of valve Y from a source Z, and to the chamber at the right of the piston from the same source through port 36^a in the piston. Slide valve 35 and piston 36 are normally held in the 25 inactive position, as shown by means of spring 94. The mechanism also comprises the engineer's brake valve M, and an engineer's acknowledging valve H, and a release pilot valve N, together with a timing valve 30 X, and an acknowledging valve Q.

The operation of the apparatus shown in Fig. 2, as the train passes along the stretch of track shown in Fig. 1, is as follows:

Assuming that the train occupies section 35 A—B, it will be observed that track circuit current and loop current of normal relative polarity are supplied to the train so that relay F is energized in the normal direction, the authorized lamp A' is lighted, and 40 the unlimited speed magnet 26^U is energized. Air pressure is supplied to the chamber above slide valves K^U and K^H from a source Z through pipes 37, 38 and 39, and to the chamber at the right of piston 51 45 from the same source through branch pipe 48, valve 49 and pipe 50, to equalize the pressure on both sides of piston 51. The unlimited speed relay valve K^U is then held in its left-hand position by means of spring 50 100, so that air pressure from the chamber above K^U passes through port 40 and pipe 42 to reservoir 33, and through pipe 43 to the chamber above diaphragm 44 of timing valve X, causing this valve to assume its 55 lower position. Air pressure is then supplied from source Z through pipes 37 and 37^a, valve 45 and pipe 46 to the chamber at the left of piston 47 of valve K^H, to equalize the pressure on both sides of piston 60 47. The high speed relay valve K^H is held in its right-hand position by means of spring 101. Since pipe 63 is "blanked" at cavity 64 in valve K^H, there is no provision for exhausting air from the chamber at the 65 right of piston 36 of the brake application valve Y, so that regardless of the speed of the train, this valve will remain in normal position, thereby preventing an automatic application of the brakes. In other words, the train can then make any speed of which 70 it is capable. An acknowledging reservoir 34 is opened to atmosphere through ports 59 and 58 in the acknowledging valve Q, pipe 71, pipe 56, and port 91 in relay valve K^U. 75 As the train enters section B—C, the relative polarity of the current supplied to winding 20 of relay F is reversed, so that this relay reverses, thereby extinguishing the authorized speed lamp A' and lighting the restricted speed lamp R'. At the same 80 time the unlimited speed magnet 26^U becomes de-energized and the high speed magnet 26^H becomes energized. The consequent reversal of valve 49 connects the chamber of piston 51 with atmosphere through pipe 50, 85 valve 49 and exhaust port 61, so that the unlimited speed relay valve K^U moves to the right. Timing valve X and consequently relay valve K^H remain unchanged in position because the chamber above diaphragm 90 44 is now supplied with air pressure from source Z through pipes 37, 38 and 48, valve 68 reversed, pipe 67, cavity 66 of K^U reversed, pipes 42 and 43 to the chamber above 95 44. The pressure existing on the right-hand face of piston 36 in the brake application valve Y is now exposed to the high speed governor valve 27^H, through pipes 52, 54 and 63, cavity 64 and pipe 65. If the speed of the train is above a given high value, such 100 as 65 miles per hour, valve 27^H is opened by stem 29 on crosshead 93, so that the brake application valve Y is shifted to the right, thereby causing an automatic application of the brakes. On the other hand, if the speed 105 of the train is below 65 miles per hour, valve 27^H is closed, so that no automatic brake application occurs.

Assuming that the speed of the train is above the given high value on entering section B—C, so that an automatic brake application occurs, the train will be brought to a full stop provided the engineer takes no action. The reason for this is that as soon as brake application valve Y is shifted to the right, a path is opened from the chamber of piston 36, through pipes 52 and 53, cavity 80 in slide valve 35, pipe 81, valve 82 and exhaust port 83 to atmosphere, so that the brake application valve remains in applying position, even though the exhaust path through valve 27^H becomes closed as soon as the speed is reduced below the given high value. Valve 82 of the release pilot valve N is held in the position shown by air from main reservoir through pipe 86, brake valve chamber 87, port 88, and pipe 84 to the chamber below piston 85 of valve N. In order to release the brakes the speed must be reduced so that valve 27^H is closed, and the engineer 125 120 125 129

must shift his brake valve M to the lap position, thereby connecting the lower piston chamber of the release pilot valve N with atmosphere through pipe 84, cavity 89 and exhaust port 90, whereupon the valve 82 closes, thereby allowing pressure to build up on the right-hand face of piston 36 through the restricted port 36^a. As soon as this pressure builds up to a given value, determined by the spring 94, the slide valve 35 will be restored to its initial position, whereupon the engineer may release the brakes by the customary manipulation of valve M, and the train may then proceed.

As the train enters section C—D, relay F will become de-energized owing to the fact that the supply of loop current to the rails of this section has been discontinued. The slow speed lamp S' will then become lighted and the high speed magnet 26^H will be de-energized. The timing reservoir 33 and the upper diaphragm chamber of the timing valve X are now connected to blow-down valve 28, through pipe 42, cavity 66, pipe 67, valve 68 and pipe 62. Blow-down valve 28 has a fixed small orifice 102 opening directly to atmosphere, and a larger variable orifice 103 which is opened by the movement of the piston of this valve by stop 31 on cross-head 93, by an amount substantially proportional to the train speed, so that the pressure in reservoir 33 and above diaphragm 44 will be reduced at a rate which is substantially proportional to the speed of the train. That is, at comparatively high speeds the pressure will be reduced in a few seconds to such value that valve X will reverse, whereas at relatively low speeds this reduction of pressure will not be accomplished for approximately 30 seconds. As soon as the valve X reverses, the pressure in the left-hand piston chamber of valve K^H will be exhausted to atmosphere through pipe 46, valve 45 and exhaust port 69, whereupon the high speed relay valve K^H will be shifted to the left. Assuming that the engineer has not acknowledged the caution indication at the entrance to the block C—D, the right-hand piston chamber of the brake application valve Y will be connected with the empty acknowledgment reservoir 34 through pipes 52, 54 and 55, port 91, pipe 70, check valve 32, pipe 71 and ports 58 and 59 of valve Q to reservoir 34. The brake application valve Y will then shift to the right, thereby applying the brakes regardless of the speed at which the train is traveling. If, however, the engineer acknowledges the caution signal prior to the reversal of valve K^H, this automatic brake application will be prevented if the speed of the train is below a given low value, such as 15 miles per hour. The acknowledging apparatus is as follows: When the handle 75 of the acknowledging valve H is in the position shown in the drawing, a reservoir 72 is charged with pressure from source Z through cavity 74 and pipe 76. To acknowledge a signal, the engineer reverses the handle of valve H, so that reservoir 72 is disconnected from source Z and its pressure flows through pipe 76, cavity 74 and pipe 77 to the lower piston chamber of valve Q, thereby lifting piston 78 and valve 60 to close port 58 and to open valve 95, thereby permitting pressure to pass from pipe 38, through pipe 57, valve 95 and port 59 to reservoir 34, so that when valve Q returns to its original position, which will occur after an interval of approximately 10 seconds, the pressure in reservoir 34 will be applied to pipe 56, and, consequently, to the upper portion of the check valve 32. When, therefore, the relay valve K^H reverses, the pressure in the right-hand piston chamber of valve Y will not be reduced sufficiently to cause piston 36 to move and so the brakes will not be applied unless the low speed valve 27^H is open. This low speed valve is opened by stem 30 in crosshead 93 if the speed of the train is above a given low value, such as 15 miles per hour. The train may therefore proceed through section C—D without incurring an automatic application of the brakes, provided that the speed does not rise above 15 miles per hour, and the train may, furthermore, proceed into the section at the right of D under the same restriction.

One important feature of my invention is that comparatively short sections may be employed, permitting close spacing of trains in congested territory. This is because means are provided for insuring that the train speed does not exceed a predetermined value at the entrance to a caution section. The stopping distance of trains at this speed, which may be determined by tests, furnishes a basis for determining the safe minimum length of section, and the sections can therefore be safely made much shorter than would be the case if it were necessary to base the section lengths upon the assumed stopping distances at the maximum speed that any train would be capable of making. This latter arrangement would be undesirable because the sections would become so long that the capacity of the road would be unduly restricted. Another feature of my invention is that the capacity of the road is less restricted than when a continuously effective high speed limit is employed, which limit, if based upon desirable section lengths, must be less than can safely be permitted when a train has a clear track ahead for two or more sections, and the signals and track are visible for long distances in advance.

One advantage of my invention is that it imposes no restrictions and permits the train to travel at any desired speed until it enters the second section in the rear of an occupied section, whereupon the speed must be re-

duced to such a value as to insure that it may be stopped, or brought to a predetermined low speed within the length of the section in the rear of the occupied section.

5 Although I have herein shown and described only one form of apparatus embodying my invention, it is understood that various changes and modifications may be made therein within the scope of the appended 10 claims without departing from the spirit and scope of my invention.

Having thus described my invention, what I claim is:

1. In combination, a stretch of railway 15 track divided into sections, means for supplying two alternating currents to the rails of each section, means responsive to the presence of a train in any one section for discontinuing the supply of one said current 20 from the section in the rear and reversing the relative polarity of one said current in the second section in the rear; and train carried apparatus controlled by said currents and operating to enforce a high speed 25 limit when both currents are present and one is of reverse relative polarity and a low speed limit when the supply of either current is discontinued, said apparatus operating to permit unlimited speed when both 30 of said currents are present and both are of normal relative polarity.

2. In combination, a stretch of railway track divided into sections, means for supplying two alternating currents to the rails 35 of each section one of which flows through the two rails in series and the other of which flows through the two rails in multiple,

means responsive to the presence of a train in any one section for discontinuing the supply of one said current from the section 40 in the rear and reversing the relative polarity of one said current in the second section in the rear; and train carried apparatus controlled by said currents and operating to enforce a high speed limit when both 45 currents are present and one is of reverse relative polarity and a low speed limit when the supply of either current is discontinued, said apparatus operating to permit unlimited speed when both of said currents 50 are present and both are of normal relative polarity.

3. In combination, a stretch of railway track divided into sections; means for each section for supplying two alternating currents of normal relative polarity to the rails when the two sections in advance are unoccupied, two alternating currents of relative polarities opposite to each other when the second section in advance is occupied 60 and the intervening section is unoccupied, and only one alternating current when the section immediately in advance is occupied; and train carried apparatus controlled by said currents and operating to enforce a 65 high speed limit when both currents are present and one is of reverse relative polarity and a low speed limit when the supply of either current is discontinued, said apparatus operating to permit unlimited speed 70 when both of said currents are present and both are of normal relative polarity.

In testimony whereof I affix my signature.
LLOYD V. LEWIS.
